DESIGN FOR A SEED PACKET DISPLAY DEVICE

Palmer E. Winslow, Detroit, Mich., assignor to
Ferry-Morse Seed Co., Detroit, Mich.

Application May 16, 1941, Serial No. 100,983

Term of patent 7 years

To all whom it may concern:

Be it known that I, Palmer E. Winslow, a citizen of the United States, residing at Detroit, in the county of Wayne and State of Michigan, have invented a new, original, and ornamental Design for a Seed Packet Display Device, of which the following is a specification, reference being had to the accompanying drawing, forming part thereof.

In the drawing:

Figure 1 is a view in elevation of a seed packet display device, showing my new design; and

Fig. 2 is a view in cross-section taken on line 2—2 of Fig. 1.

The dominant features of my design are embodied in the portion shown in solid lines in the drawing. The broken line rectangular forms represent seed packets and are merely illustrative of the manner of display thereof.

I claim:

The ornamental design for a seed packet display device, as shown and described.

PALMER E. WINSLOW.
